Des. 212,185
Patented Sept. 10, 1968

212,185

PAINT CAN LID

Thomas V. O'Leary, 1722 Martins Lane,
Gladwyne, Pa. 19035

Filed Mar. 16, 1967, Ser. No. 6,252

Term of patent 14 years

(Cl. D9—264)

Fig. 1

Fig. 2

Fig. 3

FIG. 1 is a top plan view of a paint can lid showing my new design;

FIG. 2 is an elevational view; and

FIG. 3 is an enlarged scale sectional view taken on line 3—3 of FIG. 1.

I claim:

The ornamental design for a paint can lid, as shown.
